UNITED STATES PATENT OFFICE.

OTTO WITTE, OF VINELAND, NEW JERSEY, ASSIGNOR TO GRUSHLAW & SICHEL, A FIRM COMPOSED OF GEORGE GRUSHLAW AND JOHN SICHEL, OF GERMANTOWN, PENNSYLVANIA.

DESIGN FOR A BUTTON OR SIMILAR ARTICLE.

Application filed September 18, 1924. Serial No. 10,825. Term of patent 14 years.

To all whom it may concern:

Be it known that I, Otto Witte, a citizen of the United States, residing at Vineland, county of Cumberland, State of New Jersey, have invented a new, original, and ornamental Design for Buttons or Similar Articles, of which the following is a specification, reference being had to the accompanying drawing, forming a part hereof.

Figures 1 and 2 are, respectively, plan and edge views of a button or similar article showing my new design.

I claim:

The ornamental design for a button or similar article substantially as shown.

OTTO WITTE.
